L. A. TRIPP AND S. M. BOYD, OF NEW YORK, N. Y.

Letters Patent No. 86,044, dated January 19, 1869.

IMPROVED CURTAIN-FIXTURE.

The Schedule referred to in these Letters Patent and making part of the same.

To all whom it may concern:

Be it known that we, L. A. TRIPP and S. M. BOYD, of New York, in the county of New York, and State of New York, have invented a new and useful Improvement in Window-Shade Fixtures; and we do hereby declare that the following is a full, clear, and exact description thereof, which will enable others skilled in the art to make and use the same, reference being had to the accompanying drawings, forming part of this specification, in which—

Figure 1 is a front view of a window-shade to which our improvements have been attached.

Figure 2 is an end view of the same.

Figure 3 is a detail sectional view of the same, taken through the line $x x$, fig. 1, looking to the right.

Figure 4 is the same section as fig. 3, but looking to the left.

Figure 5 is a detail perspective view of the detachable cord-guide.

Similar letters of reference indicate like parts.

Our invention has for its object to furnish simple, cheap, effective, and convenient fixtures for attachment to ordinary shade-rollers, which shall, at the same time, be so constructed and arranged as to allow the shade to be operated with the same facility as when a spring-roller is used.

It consists in the construction and combination of the various parts of the fixtures, as hereinafter more fully described.

A represents the part of the window-casing to which the brackets B and C are attached.

The bracket B is formed with a round hole to receive the roller-pivot, which pivot is attached to a circular cap or plate, and is secured to the end of the roller D by nails or screws passing through the said plate and into the end of the said roller.

To the outer side of the pivot-plate is attached a sleeve, E, in which is placed a sliding bolt, F, which is prevented from dropping out of the outer end of the sleeve E by a stop-pin, or by closing up the said outer end of the said sleeve.

As the roller revolves, the inner end of the catch-bolt F rests and rides upon the catch-block G, which is securely attached to or formed upon the bracket B, and which has a shoulder formed upon it in about the position shown in fig. 4.

If desired, the catch-block G may be omitted, and the inner end of the sliding bolt F allowed to rest and ride upon the pivot of the roller D. In this case, a stop-pin, or equivalent projection, should be attached to or formed upon the bracket B, in about the position of the shoulder of the catch-block G.

By this construction, when the shade is drawn up, or allowed to run down rapidly, the centrifugal force engendered by the rapid revolution of the roller D, throws and holds the sliding bolt F in the outer end

of the sleeve E, so that it passes freely over the catch-block G; but when the shade is allowed to move down slowly, the sliding bolt F catches upon the shoulder of the catch-block G, and stops the shade, thus enabling the said shade to be adjusted to stand in any desired position.

H is the spool, the inner flange of which is secured to the end of the roller D by nails or screws, as shown in fig. 2.

To enable the said screws or nails to be conveniently inserted, the outer flange of the spool H is cut away, so as to leave only wings, or a bar, h', upon each side of the shank or body of the spool.

The outer end of the pivot attached to or formed upon the outer end of the spool H, projects through, and works in a slot in the bracket C, as shown in fig. 2.

I is the controlling-cord, the end of which is attached to, and which is wound around the shank or body of the spool H.

The lower end of the pivot attached to or formed upon the outer end of the spool H, projects through, and works in a slot in the bracket C, as shown in fig. 2.

The cord-guide J is made in about the form shown in fig. 5, that is to say, it has a square projection formed upon the outer side of its upper end, which fits into the slot in the bracket C, and prevents the said guide from turning.

The guide J has a hole formed through its upper part, through which passes the pivot of the roller D, so that the said guide may ride upon the said pivot.

The lower end of the guide J is bent inward at right angles, and has a hole formed through it for the passage of the cord I, as shown in the drawings.

K is a button, attached to the cord I in such a position that when the shade is allowed to run down, the said button may strike against the guide J, before the shade has been wholly unwound from the roller D, so as to stop the revolution of the roller, and prevent the shade from being torn away from the said roller, as it would be liable to be if allowed to run entirely down.

By this construction, the shade is raised or wound upon the roller D, and its movement controlled, when descending, by means of the cord I; but it descends, or is unwound from said roller, by its own weight, or by the weight of itself and of the tassel or tassels attached to it.

This construction enables the shade and all its fixtures to be detached by simply removing its pivots from the brackets B and C, without its being necessary to remove any cord or take out any screws.

Having thus described our invention,
We claim as new, and desire to secure by Letters Patent—

1. The sleeve E, constructed as described, upon the

pivot-plate of the roller, and provided with the sliding bolt F , which is adapted to move circumferentially around the shouldered stop-tube formed upon the bracket B , as herein described, for the purpose specified.

2. The angular cord-guide J , hung upon the shaft of the roller, with its upper end fitting into the slotted bracket C , and its lower end perforated for the passage of the cord I , as herein described, for the purpose specified.

3. In combination with the roller D , the sleeve E ,

sliding pin F , bracket B , tubular shouldered bearing G , spool H h' , bracket C , angular cord-guide J , and weighted cord I , as herein described, for the purpose specified.

The above specification of our invention signed by us, this 10th day of June, 1868.

L. A. TRIPP.
S. M. BOYD.
